Primary Examiner—M. N. Pandozzi(74) *Attorney, Agent, or Firm*—Wallenstein Wagner & Rockey, Ltd.(57) **CLAIM**

We claim the ornamental Design for a disposable plate, as shown and described. Broken lines in the Figures form no part of the claimed design.

DESCRIPTION

FIG. 1 is a perspective view of a first embodiment of a disposable plate;
 FIG. 2 is a top plan view of the plate of FIG. 1;
 FIG. 3 is a front elevation view of the plate of FIG. 1, with an opposite view being identical thereto;
 FIG. 4 is a left side elevation view of the plate of FIG. 1;
 FIG. 5 is a right side elevation view of the plate of FIG. 1;
 FIG. 6 is a bottom plan view of the plate of FIG. 1;
 FIG. 7 is a perspective view of a second embodiment of the plate of the present invention;
 FIG. 8 is a top plan view of the plate of FIG. 7;
 FIG. 9 is a front elevation view of the plate of FIG. 7, with an opposite view being identical thereto;
 FIG. 10 is a left side elevation view of the plate of FIG. 7;
 FIG. 11 is a right side elevation view of the plate of FIG. 7; and,
 FIG. 12 is a bottom plan view of the plate of FIG. 7.
